UNITED STATES PATENT OFFICE.

VINCENT CARTWRIGHT VICKERS, OF WESTMINSTER, LONDON, ENGLAND, ASSIGNOR
TO VICKERS LIMITED, OF WESTMINSTER, ENGLAND.

DOOR-LATCH.

1,147,284.

Specification of Letters Patent. Patented July 20, 1915.

Application filed October 18, 1913. Serial No. 795,853.

To all whom it may concern:

Be it known that I, VINCENT CARTWRIGHT VICKERS, a subject of the King of Great Britain, residing at Vickers House, Broad-
5 way, Westminster, in the county of London, England, have invented certain new and useful Improvements in or Relating to Door-Latches, of which the following is a specification.

10 This invention relates to door latches of the kind that are provided with means for forcing the door open when the latch bolt is withdrawn, the said latches being more particularly intended for tightly fitting doors such as are employed on railway carriages, motor cars and other road vehicles.

According to this invention a lever or pivoted member which for sake of convenience is hereinafter referred to as a piv-
20 oted push piece is so constructed and ar-
ranged in relation to an actuating member under the control of the door handle, that the operation of the latter in the act of with-
drawing the latch bolt causes the said push
25 piece to be forcibly displaced about its pivot and to exert a thrust between the door and its jamb for forcing open the door.

In order that the said invention may be clearly understood and readily carried into effect, it will now be described more fully with reference to the accompanying drawings, in which:—

Figure 1 is a vertical section through a latch to which the improvements are applied, the latch bolt being represented in its withdrawn position. Fig. 2 is a similar view to Fig. 1 but shows the latch bolt in its protruding or locking position. In both Figs. 1 and 2 the latch is shown detached
35 from the door. Figs. 3 and 4 are horizontal sections taken approximately on the lines 1—1 and 2—2 of Figs. 1 and 2 respectively and showing the latch in position on the door. Fig. 3 shows the door partly opened
40 by the action of the push piece.

A is the body of the door and B is the lock frame which is attached thereto in any appropriate manner.

C is the cover plate carrying projections
50 which form guides c c' c" for the latch bolt

D, and the member D' that operates the pivoted push piece G. This member D' is, in the example shown, in the form of a rectangular sliding block. The latch bolt is adapted to be actuated by either of the 55 handles E or E', as is well understood, the handle E extending vertically through the latch and the body of the door so as to occupy a position for enabling the occupant of the vehicle to conveniently grasp it and 60 the handle E' being situated on the exterior of the door to enable the latch to be operated from the outside of the vehicle by a rotary movement. The said handle E is pivoted at e and extends vertically through 65 the latch bolt D and the sliding block D', which are slotted at d and d' for this purpose. The pivoted push piece G is angularly displaceable about a vertical pin g which at its inner end is screwed into the 70 lower one of two lugs c c' carried by the latch plate C. The said pivoted push piece G has three arms or projections g' g" g". The arm g' lies within a recess within the jamb of the door, the arm g" enters a slot 75 d" in the sliding block D' and the arm g" lies behind a lever J which is loosely mounted on the pin g; has its free end adapted to be acted upon by the inclined portion d'x of the sliding block D'.
80

H is a spiral spring acting upon the inner end of the latch bolt and normally tending to keep the latter in its locking position. On displacing the handle E the portion c' thereof comes into contact with the inner 85 end of the slot d of the latch bolt D and moves the latter inwardly against the resistance of the said spring H, whereupon the portion e' of the said handle comes into contact with a projection d' at the inner end 90 of the slot d' of the sliding block D' so that the continued movement of the said handle causes the sliding block D' to be moved inwardly. This movement of the sliding block D' causes its inclined portion d'x to 95 displace the lever J which exerts a powerful turning movement on the pivoted push piece G through the arm g", thus pressing the arm g' against the door jamb and forcibly pushing the door open (see Fig. 3). The push- 100

ing effort of the pivoted push piece is still further augmented by the forward portion of the slot d^2 in the sliding block coming against the arm g^2 of the pivoted push piece 5 as the said sliding block completes its inward movement. When the said handle E is released, it resumes its original position under the influence of the spring H acting on the latch bolt D, and by acting upon the 10 forward end of the slot d' in the sliding block D' returns the latter to its forward position. The closing of the door brings the nose g' of the pivoted push piece in contact with the door jamb, thereby imparting 15 the reverse motion to the sliding block D', through the arm g^2 of the pivoted push piece engaging with it, the arm g^3 on the pivoted push piece operating to return the lever J to its normal position also; the parts 20 thus assume the position shown by Fig. 4. When the door is opened from the outside by the handle E', sufficient pressure can be exerted by the operator to pull the door open without the assistance of the pivoted 25 push piece which consequently remains inoperative.

Although the invention has been described more particularly with reference to latches operated by a hand lever such as E, it is not 30 intended to be limited to this type of latch.

What I claim and desire to secure by Letters Patent of the United States is:—

1. A door latch provided with a pivoted 35 push piece, a handle which is carried by the door and indirectly connected to said push piece, and a slidable latch bolt, in combination with means whereby the act of withdrawing said latch bolt causes said push piece to be forcibly displaced about its pivot 40 and to exert a thrust between the door and its jamb.

2. In a door latch, the combination with 45 the slidable latch bolt thereof and the means for actuating it, of a pivoted push piece, an actuating member carried by the door for forcibly displacing said push piece about its pivot, and means also carried by the door for operating said member in the act of withdrawing said latch bolt and causing the 50 push piece to exert a thrust between the door and its jamb.

3. In a door latch, the combination with 55 the latch bolt and the means for actuating it, of a pivoted push piece, a slidable actuating member for forcibly displacing said push piece about its pivot, and means for operating said member from the bolt actuating means.

4. In a door latch, the combination with 60 the slidable latch bolt thereof and the means for actuating it, of a three armed pivoted push piece adapted to exert a thrust between the door and its jamb, and means carried by the door and operated from the bolt actuating

means for forcibly displacing said push piece about its pivot. 65

5. In a door latch, the combination with the latch bolt and the means for actuating it, of a pivoted push piece adapted to exert a thrust between the door and its jamb, an actuating member therefor, means for operating the actuating member during the movement of the latch bolt, and means interposed between said member and push piece for augmenting the power transmitted to the 75 push piece at the early part of its movement. 70

6. In a door latch, the combination with the latch bolt and the means for actuating it, of a pivoted push piece, a slidable actuating 80 member therefor, means for operating said member during the movement of the latch bolt, and means interposed between said member and push piece for augmenting the power transmitted to the push piece at the 85 early part of its movement.

7. In a door latch, the combination with the latch bolt and the means for actuating it, of a pivoted push piece, a slidable actuating member therefor, means for operating 90 said member during the movement of the latch bolt, a lever interposed between said member and push piece, and means whereby the sliding movement of said actuating member is transmitted through said lever to 95 the push piece at the early part of its movement.

8. In a door latch, the combination with the latch bolt and the means for actuating it, of a pivoted push piece, a slidable actuating member therefor provided with an inclined portion, means for operating said member during the movement of the latch bolt, a lever movable about the axis of the pivoted push piece and normally lying with 100 its free end adjacent to the inclined portion of said member, and an arm on said push piece with which the lever coöperates during the early part of the push piece's movement. 105

9. In a door latch, the combination with 110 the latch bolt and the means for actuating it, of a pivoted push piece, a slidable actuating member therefor provided with an inclined portion and a slot, means for operating said member during the movement of the latch bolt, a lever movable about the axis of the pivoted push piece and normally lying with its free end adjacent to the inclined portion of said member, an arm on said push piece with which the lever coöperates during 115 the early part of the push piece's movement, and a second arm on said push piece with which the slot in said member coöperates during the later part of the push piece's movement. 120

10. In a door latch, the combination with the latch bolt, a hand lever for actuating it in one direction and a spring for actuating 125

it in the opposite direction, of a pivoted push piece, a slidable actuating member therefor provided with a slot for the reception of said hand lever, and a pivot about which said hand lever moves and imparts motion to said actuating member through the intervention of the slot in the latter.

In testimony whereof I affix my signature in presence of two witnesses.
